WALKING HORSE TOY

Rudy R. Proctor, Arvada, and Denver L. Proctor, Wheat Ridge, Colo., assignors to Jet-X Corporation, Denver, Colo.

Filed Jan. 29, 1971, Ser. No. 111,167

Term of patent 14 years

Int. Cl. D21—01

U.S. Cl. D34—15

Fig. 1

Fig. 2

Fig. 3

Fig. 4

Fig. 5

Fig. 6

FIG. 1 is a right side perspective view of a preferred form of our ornamental design, the left side thereof being similar in appearance.

FIG. 2 is a front elevational view thereof.

FIG. 3 is a rear elevational view thereof.

FIG. 4 is a right side perspective view similar to FIG. 1 but depicting a variation wherein the head and mane are a closer simulation of a horse head.

FIG. 5 is a front elevational view of the design shown at FIG. 4.

FIG. 6 is a rear elevational view of the design shown at FIG. 4.

We claim:

The ornamental design for a walking horse toy, as shown and described.
